Primary Examiner — Vy N Koenig(74) *Attorney, Agent, or Firm* — Smyrski Law Group, A P.C.(57) **CLAIM**

The ornamental design for a seating device, as shown and described.

DESCRIPTION

FIG. 1 is a top perspective view showing the top, front, and right sides of a seating device;

FIG. 2 is a bottom perspective view showing the bottom, rear, and left sides of the seating device;

FIG. 3 is a front elevation view of the seating device;

FIG. 4 is a rear elevation view of the seating device;

FIG. 5 is a right side elevation view of the seating device;

FIG. 6 is a left side elevation view of the seating device;

FIG. 7 is a top plan view of the seating device; and,

FIG. 8 is a bottom plan view of the seating device.

The broken lines in the drawings depict portions of the seating device that form no part of the claimed design.

1 Claim, 7 Drawing Sheets(56)
